CLUTCH CONTROL MECHANISM

Maurice Windelinckx, Brussels, Belgium

Application May 12, 1930, Serial No. 451,760
In France May 15, 1929

1 Claim. (Cl. 192—.01)

My invention relates to an automatic device for operating the clutch mechanism of a mechanically propelled vehicle.

In motor vehicles or other means of locomotion the object of the clutch is to couple or uncouple an engine to the transmission. This clutch is generally actuated by a pedal or by a lever.

The object of the present invention is to suppress this effort by providing a device making use of the vacuum existing in the intake manifold of an internal combustion engine.

According to the invention the pressure variations which occur in such a reduced pressure system according to the operating conditions of the engine are employed to actuate a distributor valve which serves to connect a vacuum servomotor, for moving the clutch mechanism, either to a reduced pressure system or to the atmosphere.

20 The invention will be more particularly described with reference to the accompanying drawing, in which Figures 1 and 2 are sectional views representing two working positions of a preferred construction of the device.

25 When an engine is running at a normal driving speed, the throttle of the carburettor being partly or entirely open, the degree of vacuum in the induction piping does not differ very greatly from the atmospheric pressure. On the contrary, 30 when the engine is running at slow speed, the said vacuum is considerably increased, owing to the fact that the throttle of the carburettor is in its extreme position of closing. Using this fact as a basis, it is possible to construct an automatic 35 distributor which by connecting a vacuum servomotor coupled to the clutch mechanism to the intake-manifold, will cause declutching as soon as the engine slows down.

Such a distributor consists of a cylinder 18, in 40 which a piston 19 slides. The said piston is provided with an air port 20 and a vacuum port 21, which may, respectively, communicate at certain moments with an air port 23 and a vacuum port 22 leading to the servo-motor cylinder 4. An air-tight wall 26 of the piston 19 divides the cylinder 18 into two distinct chambers 27 and 28. The chamber 27 communicates with the source of 45 vacuum by the pipe 7. The chamber 28 is subjected to atmospheric pressure by the orifice 8.

50 A spring 24, suitably calibrated, normally maintains the piston 19 in a position such that the port 20 communicates with the port 23, establishing atmospheric pressure in the interior of the cylinder 4 (clutching period, Fig. 1).

55 When the throttle is closed and the engine slows down the value of the vacuum in the chamber 27 increases in proportions sufficient to draw back the piston 19, while overcoming the action of the spring 24. The said piston closes the port 23 and uncovers the port 22, establishing in the

cylinder 4 the vacuum existing in the chamber 27 and the pipe 7. The declutching piston 9 is then compelled to move in the direction provided for effecting declutching (Fig. 2).

When opening the throttle, the degree of vacuum falls, and the distributor piston 19 takes up its initial position owing to the spring 24, closes the port 22 and uncovers the air port 23. The clutch is again engaged. A slotted slide 25 in the connecting rod 11 enables clutching and de-clutching to be effected by the foot of the operator in the usual manner, without moving the parts constituting the automatic clutching mechanism, provided the declutching pedal 10 is retained.

15 A detachable nozzle 8^a on the air inlet 8 and nut 7^a in the vacuum pipe 7 enable calibrated openings of different diameters to be provided, which give an adjustment insuring a more or less rapid movement of the piston 9 in the cylinder 4, 20 which adjustment is determined by experiment according to the strength of the clutch springs.

The invention thus covers the principle of automatic declutching by the sole effect of the increase in vacuum in the induction piping of the engine when communication between the said piping and the carburettor has been throttled sufficiently by releasing the accelerated pedal partly or entirely.

What I claim is:

30 In an automatic clutch operating mechanism for motor vehicles having a source of vacuum, a servo-motor cylinder, a servo-motor piston in the cylinder connected to the clutch operating member, a distributor device for controlling the partial vacuum in the servo-motor cylinder, said distributor device comprising a casing and a distributing member movable therein, and having a surface subjected to the sub-atmospheric pressure of the source of vacuum and a second surface 40 subjected to the pressure of the atmosphere, a resilient means acting upon the said first mentioned surface in a direction opposite to that of the sub-atmospheric pressure, a vacuum inlet port between the servo-cylinder and the distributor casing, a vacuum inlet port on the distributor member to register with said first mentioned vacuum inlet port after displacement of said distributing member, under the action of increase of vacuum in the vacuum source when 45 the carburettor throttle is in its closing position, an air inlet port between the servo-cylinder and the distributor casing, and an air inlet port in said distributing member to register with said first mentioned air inlet port after displacement of said distributing member under the action of said resilient means when the degree of vacuum is decreased, due to the opening of the throttle valve.
